Henry C. Fay Design

Patented March 6th 1849

No 210

TD23-128

Des. 210

Henry C Fay Troy, New York

Letter's Patent No. 210 dated Mar 10, 1840, illustrated Oct 2, 1845

The schedule referred to in these Letters Patent and
on a flying part of the same.

To whom it may concern. Be it known that Henry C Fay
of Troy in the County of Rensselaer and the State of New
York have invented or produced a new design figure

or pattern for cooking stoves which is described as follows: reference being had to the annexed drawing, making part of this specification.

The drawing represents the right hand jamb (a side plate) with the oven doors close down, which A is the large lower oven door, B the small or upper oven door and C the panel against the fire box, the two latter (B & C) having each a ind curved like the sides of a gothic arch thereby giving the stove a symmetrical appearance the other left hand jamb is the same except the upper oven door B is on the left of the panel C (The same to be known as "Eureka Circulating Hot air Cook stove")

What I claim and desire to secure by letters patent is the production of a new set of Stove patterns herein described

Witnesses.

J. Forayth

R. W. Duncan.
